UNITED STATES PATENT OFFICE.

JOSEPH C. VENABLE, OF EAST ST. LOUIS, ILLINOIS.

EMERGENCY ANGLE-CO尤LING FOR BROKEN TRAIN-LINES.

1,304,126.

Specification of Letters Patent.

Patented May 20, 1919.

Application filed April 15, 1918. Serial No. 228,514.

To all whom it may concern:

Be it known that I, JOSEPH C. VENABLE, a citizen of the United States, residing at East St. Louis, in the county of St. Clair and State of Illinois, have invented a new and useful Emergency Angle-Coupling for Broken Train-Lines, of which the following is a specification.

My invention relates to an emergency angle-coupling to take the place of an angle-cock which has been broken off the train line or removed for any cause.

The object of my invention is to provide a simple device which may be easily and quickly affixed to the air-pipe of a train-line, by the train crew, to take the place of an angle-cock which has been broken off the train line thereby obviating the necessity of removing the car from the train which has the broken train-line or switching the car to the front of the train next to the engine, or to the rear thereof next to the caboose.

With the above and other objects in view, the invention consists in certain novel features of construction, arrangement and combination of parts as will be more fully described hereinafter and finally pointed out in the claims hereto appended.

Referring to the accompanying drawings forming a part of this specification wherein like characters of reference denote similar parts throughout the several views:

Figure 1, is a diagram of a train-line section under a car showing the usual angle-cock at one end and my invention or emergency angle-coupling affixed to the other end thereof in lieu of an angle-cock.

Fig. 2, is a sectional view of my angle-coupling affixed to a train-line pipe at one end thereof where the usual angle-cock has been broken off.

Fig. 3, is a sectional view taken on line A—A of Fig. 1, but on a larger scale.

Fig. 4, is a detail in perspective of one of the pipe clamping-segments.

Referring to the accompanying drawings the reference character 1 designates the air-pipe of a train-line which is located and carried under a car and connected between the cars by means of the usual air-hose 2 and the usual angle-cock connection 3.

In carrying out the aim of my present invention I employ a female coupling member 4 which is interiorly threaded as at 5. Member 4 is provided with an end wall 6 termi-

nating in a suitable neck 7 provided with an angular passage 8. The outer end of the neck 7 is interiorly threaded, as at 9, to receive the usual nipple 10 of an air-hose 11. The neck 7 is also preferably provided with a suitable wrench gripping shoulder 12.

A male member 13 is employed having the exteriorly threaded surface 14 adapted for screw-threaded engagement with the female member 4, as clearly shown in Fig. 2 of the drawings. The male-member 13 is also provided with a suitable wrench gripping shoulder 15, as shown in Figs. 1 and 2 of the drawing so as to be able to hold the same stationary while tightening member 4 thereon.

The male member 13 is provided with the air-pipe receiving opening or passage 16 through which is adapted to pass the broken end of a train line air-pipe designed 1.

The male member 13 is further provided with a tapered or cone receiving chamber 17 having the shoulder 18 adjacent the wrench-gripping end 15 thereof.

A pair of suitable preferably semi-circular pipe clamping segments 19 having a tapered periphery 20 to correspond to the tapered wall of the receiving chamber 17 is adapted to be carried in the receiving chamber 17 between the shoulder 18 and the end-wall 6 of the female member 4, as clearly shown in Fig. 2.

Each cone segment 19 is provided with a semi-circular passage 21, in cross-section, adapted to form a tubular passage when they are assembled, as shown in Fig. 3, to receive the train-line air-pipe 1.

A suitable packing ring 22 is interposed between the end wall 18 of the member 13 and the end faces 23 of the pipe clamping segments 19. A similar packing ring 24 is also interposed between the end wall 6 of the female member 4 and the end faces 25 of the pipe clamping segments 19.

It will be here observed that when the several parts hereinabove described are assembled upon the broken end of a train line air pipe, as illustrated, that by tightening the member 4 upon the member 13 that the pipe clamping segments 19 are forced or wedged to tightly grip the broken train line pipe 1 and also force or wedge its end faces 23 and 25 tightly against the packing rings 22 and 24, respectively to provide an air tight connection around and adjacent the pipe 1 at 110

each end of the pipe clamping segments 19, as clearly shown in Fig. 2.

It will readily be understood from the foregoing specification that should the usual angle-cock 3 be broken off the train-line pipe 1 due to any cause or removal for repair that my angle-coupling can be readily and quickly applied in lieu thereof, thereby providing an emergency coupling which will 10 effectively carry out all the functions of the usual angle-cock excepting the function of the usual cut-off which is not necessary for an emergency coupling owing to the fact that the emergency coupling may be removed at the end of a run and a new angle-cock fixed to the train line pipe 1, as is 15 manifest.

Broken train lines are a source of nuisance to train men and the cause of unnecessary 20 delay on the road and the cause is usually due to the angle-cock being broken off of the pipe 1 which is caused usually by the weakening of the pipe at the threaded connection with the angle-cock.

25 My angle-coupling may be carried by the train crew in the engine or in the caboose and may be applied quickly to a train line pipe when the occasion arises for its use.

The many advantages of the herein described 30 invention due to the construction shown and method of application and adjustment to a broken train line pipe will be readily apparent to those skilled in the art to which the invention appertains.

35 While I have described the principle of application to a train line pipe and adjustment of the invention thereon, together with the structure of device I now consider to be the best embodiment thereof, I desire to 40 have it clearly understood that the device shown is merely illustrative and that I reserve the right to make any such changes or modifications as may fairly fall within the principle of the invention and within the 45 scope of the appended claims when fairly construed.

What I claim is:

1. A coupling comprising a coupling body having a conical opening and adapted to 50 encircle a pipe, split cone shaped clamping segments receivable in said conical opening and adapted to engage a pipe, a second coupling member for threaded engagement with said first mentioned coupling member and 55 adapted to completely conceal said clamping segments and bring them into forced engagement with the pipe and a packing arranged at each end of the clamping segments to prevent end leaks.

60 2. In an angle-coupling for a train line, the combination of split cone-shaped clamping segments, interlocking means for securely locking the clamping segments against movement on the train-line pipe and 65 packing arranged at each end of the clamp-

ing segments to prevent end leak, means for connecting an air-hose to one end of the coupling.

3. An angle-coupling comprising a male-member adapted to be carried by a train line 70 pipe, a female member having interlocking engagement with said male member, pipe clamping means carried within said male member and adapted to forcibly engage the pipe, and means formed at one end of said 75 female member adapted for connection with an air-hose.

4. In a device of the class described, a coupling body adapted to be carried by a train-line pipe, split clamping segments 80 carried within said coupling body and adapted to encircle the pipe, interlocking means for completely concealing the clamping segments and for wedging said clamping segments around the pipe packing arranged 85 at each end of the clamping segments to prevent end leak, and an air-hose connection formed at one end of said coupling body.

5. In a device of the class described, a coupling body adapted to be carried by a train-line pipe, pipe clamping means carried within said coupling body adapted to encircle the pipe, means for wedging said clamping means around the pipe, a packing positioned at each end of said pipe clamping 95 means and an air-hose connection formed at one end of said coupling body.

6. In a device of the class described, a coupling body formed by means of a female member and male member having interlocking connection and having a cone clamp receiving chamber and an air passage, cone shaped clamping means carried within said cone clamp receiving chamber adapted to encircle and be wedged into engagement 100 with the outer surface of the pipe, packing rings positioned at each end of said clamping means to prevent end leak and an air-hose connection formed at one end of the air passage of the coupling body. 105

7. In a device of the class described, a two piece coupling body, one section of said coupling body having a cone shaped pipe clamp receiving chamber, a split cone pipe clamp receivable in said chamber and adapted to encircle a train-line pipe, interlocking means for the coupling body for wedging said split cone pipe clamp into engagement with the outer surface of the train-pipe, packing means positioned at each end of said pipe clamp to prevent end leaks around the train-pipe, the other section of said coupling body having an air-passage formed therein and a threaded hose-connection formed at one end of said air-passage. 110

8. In an angle-coupling of the class described, a two piece coupling body having interlocking engagement and one section of the body having a cone shaped cavity, split cone shaped clamping means receivable in 115

- the cone-shaped cavity adapted to encircle a train line pipe, and means formed at one end of the coupling body to provide an air-hose connection.
- 5 9. An emergency angle-coupling adapted to temporarily take the place of a broken angle-cock on a train pipe line, consisting of a pair of cone-shaped clamping segments of equal size and shape, adapted to encircle 35 an air pipe, interlocking means for completely concealing the clamping segments and tightening the clamping segments about the pipe, and a packing arranged at each end of said clamping segments adapted to prevent end leak.
- 10 10. In a device of the class described, split cone shaped clamping means adapted to encircle a train pipe near the end thereof, a two piece interlocking coupling body 40 adapted to receive and conceal the clamping means and force the clamping means into frictional engagement with the pipe, and a packing positioned at each end of said clamping means to prevent end leak.
- 15 11. In a device of the class described, split cone shaped clamping means adapted to encircle a train pipe near the end thereof, a two piece interlocking coupling body adapted to receive and conceal the clamping means and force the clamping means into frictional engagement with the pipe, a packing posi- 45
- 20 tioned at each end of said clamping means to prevent end leak and an air-hose connection formed at one end of said interlocking coupling body to establish an unbroken air-line between the train-line pipe and the air-hose. 35
- 25 12. An emergency angle-coupling for broken train line pipes, comprising split clamping means adapted to engage the pipe 40 and interlocking means for completely concealing and forcing the clamping means to tightly engage the pipe and establish an unbroken train line pipe service until a new angle-cock can be fixed to the broken pipe. 45
- 30 13. A coupling having means which is 50 slidable and concealable within the coupling and capable of clamping engagement with the end of a broken train line pipe and adapted to act as an emergency coupling until a new angle cock can be fixed to the broken train pipe.
- 35 14. A coupling having means concealed therein which is clampable upon the broken end of a train pipe line and adapted to act 55 as an emergency coupling until the broken pipe can be re-threaded and a new angle cock fixed thereto.

In testimony whereof, I have hereunto signed my name to the specification.

JOSEPH C. VENABLE.
